FINGER RING

Elizabeth Palliser, New York, N. Y.

Application November 19, 1942, Serial No. 466,214

8 Claims. (Cl. 63—15)

My invention relates generally to finger rings, and in particular to finger rings within the head of which display members are disposed.

The main object of my invention is the provision of a hollow-head finger ring having a plurality of linked-together display members removably disposed within the ring head.

Another object of my invention is the provision of a finger ring having an enlarged hollow head, in which a plurality of display members are secured for sliding movement into and out of the head, and which may be entirely removed from within the head for viewing.

Another object of my invention is the provision of a hollow-headed ring having a pair of trackways therewithin in which trackways a plurality of display members may be engaged for sliding movement into and out of the head, the display elements being entirely disengageable from the tracks and removable from the head.

Still another object of my invention is the provision of a hollow-head finger ring having a pair of trackways in the side walls thereof, the trackways being narrow at the bottom of the head near the front thereof, and substantially wider at the rear thereof.

A still further object of my invention is the provision of display members for a hollow-head finger ring which may be locked therewith for sliding movement in and out of the head and easily and quickly withdrawn therefrom, as desired.

Still another object of my invention is the provision of a ring having a chamber in an enlarged head thereof, display elements disposed and secured therewithin for reciprocating sliding movement parallel to the plane of the chamber, the display element being removable from within the chamber upon angulation of the element with respect to the plane of the chamber.

Other and further objects will be apparent from the following description of an illustrative embodiment of my invention.

In the drawing annexed hereto, forming a part hereof,

Figure 1 is a side elevational view of one form of ring constructed according to and embodying my invention;

Fig. 2 is a similar view of the head of the ring, slightly enlarged and partly broken away, and with the side cover plate in raised position;

Fig. 3 is a section on the line 3—3 of Fig. 1 with the side cover plate in closing position;

Fig. 4 is a section similar to Fig. 3 through the

head of the ring with the display element components in extended position;

Fig. 5 is a side elevational view showing the manner in which the display elements are inserted into and removed from the head; and

Fig. 6 is a top plan of the linked together display elements.

My ring, indicated generally by reference numeral 10, comprises a head 12 and a conventional finger encircling portion 14. The ring may be formed in any of the conventional ways, except that head 12 thereof is enlarged and hollowed out to form a rectangular chamber 16 defined by side walls 20, 22, rear wall 21, bed 23, top 25 and front opening 18. Opening 18 is at the front of chamber 16, but at the side of the ring, and I will refer to it as a lateral opening. The ring may be decorated by suitable indicia or engraving on top 25 or on the ring ends or shoulders 27, 21.

I form a pair of trackways 30, 32 countersunk or recessed in side walls 20, 22, respectively, parallel to bed 23 and opening off the level of said bed. At the front of chamber 16 and extending past the center thereof, trackways 30, 32 are located at the bottom of the chamber and are relatively narrow, constituting merely lateral grooves in said side walls. Past the center of the chamber, however, the upper edge of the trackways curves upwardly along line 31, and the grooves expand in width to extend the full height of chamber 16 (see Fig. 4), as at 24.

I provide a plurality of display elements, which are preferably thin, flat, stamped or otherwise formed plates 40, 40, linked together at the ends thereof as at 42. Plates 40 are narrower than the width of lateral opening 18 and are shorter than chamber 16, so that when folded over atop one another, all the plates may readily fit and be received within chamber 16, as seen in Fig. 3.

The rearmost plate 44 is the same width and length as the median plates 40, and has formed thereon an outwardly extending finger 46 on each side thereof, near its terminal end. Fingers 46 are formed of such length and thickness as to fit easily within trackways 30, 32.

In order to insert the display members into the chamber 16, plate 44 must be held at an angle (see Fig. 5) and introduced into the chamber in such angled position. Fingers 46, extending laterally of plates 44, 46 prevent insertion in any other way, because the width of opening 18 is less than the lateral distance from finger to finger across plate 44. The diagonal distance 55 across opening 18, however, is longer than the

distance across fingers 46, 46, and when held in the angular position, there is no resistance to the insertion of plate 44 within chamber 16. When plate 44 has been inserted up to or past point T (see Figs. 3 and 4), the widened grooves of trackways 30, 32—increasing the lateral distance from side wall to side wall across chamber 16—permit the plate to be swung into position parallel to and atop bed 23, with fingers 46, 46 resting beneath the shoulders S defining the trackways. The display elements, after being folded on top of the plate 44, may thereafter be slid in and out of the chamber 16 in parallelism to the plane of the chamber. My linkage of elements may thus be slidable in and out of chamber 16 parallel to the plane thereof. When the fingers are at the widened rear of the chamber, the fingers may be disengaged from the tracks by the angulation of the end plate 44, and the display elements entirely withdrawn from the chamber in such angled position.

At the end of the linkage of display elements remote from plate 44, I provide and secure, as by linkage, a cover plate 50, the body 52 of which is of such size and shape as to fit within opening 18. A tongue 54, integral with and depending from body 52 is force-fitted into a suitable groove or recess 56 in the side of the ring bed, to lock plate 50 flush with the body of the ring head (see Fig. 3). Tongue 54 may be movably engaged from below to draw same from groove 56 and thereby withdraw all the display elements from the head of the ring.

Hollow head rings have been known in the art, but none having members which may be entirely removed from the head or replaced as in accordance with my invention. Photographs, names, numbers, etc., may be mounted on or engraved on my display elements. They may be withdrawn easily and quickly for viewing, they may be removed entirely with no difficulty, and a completely differently decorated set of elements may be used with the ring as desire dictates or as necessity commands.

For viewing, the elements may be withdrawn or even entirely removed from chamber 16 and unfolded into the form of Fig. 6. When it is desired to replace the elements, end plate 44 is inserted and track-engaged, and the elements folded over against one another onto end plate 44 (see Fig. 3) and slid back into the chamber, the cover plate 50 then being dropped down and locked into place to close the opening 18, at which time the outline of the ring will be smooth and unbroken, and the ring will appear just like any ordinary large head finger ring.

Having now described my invention, what I claim and desire to secure by Letters Patent is:

1. A finger ring having an enlarged hollow head, a chamber within said hollow head having a lateral opening thereinto, and a pair of opposing tracks in the side walls of the chamber, the tracks extending from front to back of the chamber, being substantially wider at the rear thereof than at the front.

2. A finger ring having an enlarged hollow head, a chamber within said hollow head having a lateral opening thereinto, and a pair of opposing tracks in the side walls of the chamber, the tracks extending from front to back of the chamber near the bottom thereof and increasing substantially in width towards the rear thereof, extending from top to bottom of the chamber at said rear.

3. A finger ring having an enlarged hollow

head, a chamber within said hollow head having top, bottom, rear and a pair of side walls, and a lateral opening thereinto, and a pair of opposing grooves countersunk in the side walls of the chamber constituting tracks parallel to and near the bottom thereof, the tracks extending from front to back of the chamber and being substantially wider at the rear than at the front thereof, the lower edge of the groove being parallel to the bottom of the chamber and the upper edge thereof being parallel to the lower edge near the front of the chamber and curving upwardly past the center of the chamber to near the top thereof.

4. A finger ring having an enlarged hollow head, a chamber therewithin defined by a pair of side walls, a rear wall, a bottom and a top, and having a lateral opening thereinto, a pair of opposing tracks in the side walls extending from front to rear of the chamber, the tracks being wider at the rear of the chamber than at the front thereof, a display element, and means thereon to engage the tracks for sliding movement therealong in and out of the chamber, the said means being disengageable from the track at the rear of the chamber permitting withdrawal of the display element from the chamber.

5. A finger ring having an enlarged hollow head, a chamber therewithin defined by a pair of side walls, a rear wall, a bottom and a top and having a lateral opening thereinto, a pair of opposing tracks in the side walls extending from front to rear of the chamber, a display element and means thereon to engage the track for sliding movement of the element in parallel relation to the bottom into and out of the chamber, the tracks at the rear thereof being wider to permit angulation of the display element with respect to the bottom and disengagement of the engaging means from the tracks, thereby permitting withdrawal and removal of the element from the chamber.

6. A finger ring having an enlarged hollow head, a chamber therewithin defined by a pair of side walls, a rear wall, a bottom and a top, and having a lateral opening thereinto, a pair of opposing tracks in the side walls extending from front to rear of the chamber the tracks being wider at the rear of the chamber than at the front thereof, a plurality of linked-together display elements, and means on one thereof to engage the track for sliding movement therealong in and out of the chamber in parallelism to the plane of the chamber, the said means being disengageable from the track at the rear of the chamber upon angulation of the element with respect to the chamber, thereby permitting complete disassociation of the display elements from the chamber.

7. A finger ring having an enlarged hollow head, a chamber therewithin defined by a pair of side walls, a rear wall, a bottom and a top and having a lateral opening thereinto, a pair of opposing tracks in the side walls extending from front to rear of the chamber, said tracks being of increased width at the rear of the chamber, a plurality of display elements and means on one thereof to engage the track for sliding movement of the element in parallel relation to the bottom into and out of the chamber, the tracks at the rear thereof permitting angulation of the display element with respect to the bottom and disengagement of the engaging means from the tracks, thereby permitting complete withdrawal and removal of the elements from the chamber.

8. A finger ring having an enlarged hollow head, a chamber within said hollow head having a lateral opening thereinto, and a pair of opposing tracks in the side walls of the chamber, the tracks extending from front to back of the chamber near the bottom thereof and increasing substantially in width towards the rear thereof, a

plurality of display elements, one thereof to engage the tracks for sliding movement of the elements into and out of the chamber, and another thereof closing the lateral opening when all of the elements are within the chamber.

ELIZABETH PALLISER.
